UNITED STATES PATENT OFFICE.

FRANK H. KAYLER, OF ALLIANCE, OHIO, ASSIGNOR TO AMERICAN STEEL FOUNDRIES,
OF CHICAGO, ILLINOIS, A CORPORATION OF NEW JERSEY.

UNCOUPLING DEVICE.

Application filed August 11, 1924. Serial No. 731,338.

This invention relates to draft mechanism and more particularly to a coupler uncoupling device that not only controls the coupling and uncoupling action, but also moves 5 the coupler sidewise to facilitate coupling of cars.

One object of the invention is to provide a simple, efficient and durable arrangement whereby a lock lifter may be given an un- 10 locking movement and also the coupler a sidewise movement to facilitate positioning the coupler for a coupling action on curves or to place the coupler in a position such that it may meet with an associated coupler 15 under various circumstances.

Another object is to provide a simple uncoupling arrangement in which, after the lock lifter is lowered into a given position, the uncoupling rod will not rest upon the 20 lifter and accordingly will not transmit weight thereto to cause a jamming of said lifter within the coupler head.

Another object is to provide a simple uncoupling device adapted to meet the various 25 requirements under service conditions.

These and other objects are accomplished by means of the arrangements shown on the accompanying sheet of drawings in which—

Figure 1 is an end view of a coupler and 30 associated parts embodying my invention.

Figure 2 is a top plan view of the arrangement shown in Figure 1.

Figure 3 is a side elevation of the arrangement shown in Figure 1.

Figure 4 is an enlarged detail view showing 35 the manner in which the uncoupling rod is connected to the lock lifter and,

Figures 5 and 6 are detail top plan and 40 side elevational views of a modified connection between the uncoupling rod and lock lifter.

The various novel features of the invention will be apparent from the following description and drawings and will be particularly pointed out in the appended claims.

Referring to the figures of the drawing, it will be noted that my invention is illustrated in connection with a standard type of car coupler having a head 10 in which the 45 knuckle 11 is pivotally mounted by a pin 12, a lock lifter 13 being provided for lifting the lock during an uncoupling movement and for permitting the lock to be lowered. Preferably the lock lifter 13 is operatively connected to the lock in the manner shown in

the Bazeley Patent No. 1,144,315, granted June 22, 1915.

An uncoupling rod 14 is provided for lifting the lock lifter 13 and its associated lock and for permitting a lowering movement of 60 same. This uncoupling rod has an operating handle 15 located near the side of the car at the end thereof, which handle extends at right angles with respect to the main length of the rod and normally extends 65 downwardly. Adjacent the coupler, the uncoupling rod is bent at right angles at 16 to the main body portion of the rod and extends outwardly over the coupler substantially in a horizontal plane and terminates 70

in a flattened eye portion 17 which embraces or surrounds the upper end of the lock lifter 13. The uncoupling rod 14 is connected to the lock lifter 13 by a pin or projections or 75 equivalent 18 associated with a saddle member 19, said pin or projections or equivalent 18 passing through an opening 21 in the upper end of the lock lifter 13, it being noted that said connecting means 18 passes

through the lock lifter 13 at a point above 80 the eye portion 17 of the lock lifter. Accordingly, when the handle 15 of the uncoupling rod 14 is raised, the eye portion 17

engages the side walls 20 of the saddle 19 for lifting the lock lifter 13 and the lock 85 connected thereto. The lifter is raised substantially in a vertical straight line throughout the lifting movement by virtue of the fact that the forwardly extending eye portion of the uncoupling rod does not move

far out of its horizontal plane and further by virtue of the fact that the uncoupling rod 14 is free to move forwardly and rearwardly in the elongated opening 22 of a bracket 23 secured to a properly supported plate 24.

By means of the connection between the eye portion 17 of the uncoupling rod and the lock lifter 13, it will be appreciated that when the uncoupling rod has been lowered 90 into the position shown in Figures 1, 3 and

4, said eye portion 17 will rest directly on top of the coupler head and will not exert any downward pressure upon the lock lifter 13 and accordingly will prevent the latter

from jamming or otherwise becoming dis- 100 arranged within the coupler head. As a matter of fact, the lock lifter 13 may be said to be suspended upon the eye portion 17 of the uncoupling rod 14 and accordingly limits

downward movement of the lock lifter 13. 105 110

In Figures 5 and 6 there is shown a modified connection between the lock lifter and the uncoupling rod in which it will be noted that a key 25 is inserted through the opening 26 in the lock lifter at a point above the eye portion 27 of the uncoupling rod. The key after being inserted is bent to curve around as at 28 to engage parts of the eye portion 27 of the uncoupling rod. This connection functions in substantially the same manner as the connection in Figures 1 and 4 in the drawing.

In addition to the uncoupling rod being capable of operating the lock lifter 13, it is capable of giving the coupler sidewise movement to position the coupler to facilitate its connection with an associated coupler. For example, if the car to which the coupler is attached is on a curve and it is desired to make a coupling, it may be necessary to move the coupler sidewise from its central position. In that case by applying a sidewise pressure upon the handle 15 in a proper direction, the coupler will be moved in the same sense by virtue of the connection of the uncoupling rod 14 to the coupler through the lock lifter 13. By referring particularly to Figure 2 of the drawing, it will be noted that the uncoupling rod is given sufficient freedom of movement to move the coupler to either side, such freedom of movement being permitted because of the elongation of the opening 22 in which the uncoupling rod operates. Said uncoupling rod in addition to being supported in the bracket 23 is also supported in a bracket 29.

By means of the arrangement herein disclosed the lock lifter and lock may be raised, the uncoupling rod being so connected with the lock lifter that no downward pressure is exerted upon the latter but as a matter of fact the downward movement of the lock

lifter is limited by the uncoupling rod resting upon the coupler head and in addition thereto the coupler may be given sidewise movement for positioning the coupler to facilitate a coupling action with an associated coupler.

What I claim as new is:

1. In draft mechanism, the combination of a coupler having a lock lifter, and an uncoupling rod embracing said lock lifter and connected thereto whereby when said rod has permitted lowering of the coupler lock, said rod will rest upon the coupler to relieve said lifter of pressure to prevent jamming of said lifter within the coupler head, said coupler being moved sidewise by said rod solely through said lifter.

2. In draft mechanism, the combination of a coupler having a lock lifter, and an uncoupling rod connected to said lock lifter for operating the latter and for giving said coupler a sidewise movement by pressure exerted solely upon said lock lifter, said uncoupling rod and lock lifter being slidably connected to each other whereby when said rod has permitted lowering of the lock lifter, said rod will rest upon the coupler to relieve said lifter of any pressure to prevent jamming of said lifter within the coupler head.

3. In draft mechanism, the combination of a coupler having a lock lifter, an uncoupling rod having a portion embracing said lock lifter whereby said coupler may be moved sidewise by said rod through said lifter, and a support for said uncoupling rod having an elongated opening for permitting freedom of movement of said uncoupling rod as the coupler is moved sidewise.

Signed at Alliance, Ohio, this 8th day of Aug., 1924.

FRANK H. KAYLER.
